(57) **CLAIM**

The ornamental design of an electronic vaporization device, as shown and described.

DESCRIPTION

FIG. 1 is a top, right, front perspective view of an electronic vaporization device showing our new design.

FIG. 2 is a top, left, back perspective view of the device as shown in FIG. 1.

FIG. 3 is a top view of the device as shown in FIG. 1.

FIG. 4 is a left view of the device as shown in FIG. 1.

FIG. 5 is a right view of the device as shown in FIG. 1.

FIG. 6 is a front end view of the device as shown in FIG. 1. FIG. 7 is a back end view of the device as shown in FIG. 1; and,

FIG. 8 is a bottom view of the device as shown in FIG. 1. The dotted lines in the drawings depict portions of the electronic vaporization device that form no part of the claimed design. The dot-dash lines in the drawings define the boundary of the claim and the claimed subject matter extends to the boundary but does not include the boundary.
